(57) **CLAIM**

We claim the ornamental design for a plant growing apparatus, as shown and described.

DESCRIPTION

FIG. 1 is a front, top perspective view of a plant growing apparatus, showing the new design;

FIG. 2 is a front, top perspective view thereof, shown in an alternate position of use;

FIG. 3 is a top view thereof, shown positioned as in FIG. 1;

FIG. 4 is a front view thereof;

FIG. 5 is a left side view thereof;

FIG. 6 is a rear view thereof; and,

FIG. 7 is a rear, bottom perspective view thereof.
